UNITED STATES PATENT OFFICE.

ANDREW ADAM, OF KENDALLVILLE, INDIANA.

WIRE-FENCE-STRETCHING DEVICE.

No. 830,553.

Specification of Letters Patent.

Patented Sept. 11, 1906.

Application filed March 23, 1906. Serial No. 307,758.

To all whom it may concern:

Be it known that I, ANDREW ADAM, a citizen of the United States, residing at Kendallville, in the county of Noble, in the State of Indiana, have invented certain new and useful Improvements in Wire-Fence-Stretching Devices; and I do hereby declare that the following is a full, clear, and exact description of the invention, which will enable others skilled in the art to which it appertains to make and use the same, reference being had to the accompanying drawings, which form part of this specification.

My invention relates to improvements in wire-fence-stretching devices.

It is well known that the present method of taking up the slack in wire fences when it is desired to secure one end to a terminal post is to stretch one wire at a time and then 20 staple them consecutively to the post, the fence-wire being in the meantime secured by various devices in close proximity to the terminal post.

The primary object of my present invention is to provide a comparatively cheap, simple, efficient, and convenient means for stretching all the longitudinal fence-wires simultaneously and uniformly to a point past the terminal post and then firmly securing 30 them in such position to enable the operator to conveniently staple the fence-wires to the post at his leisure.

Another object is to provide an improved means for raising or lowering the point of draft on fence-wires uniformly and simultaneously during the operation of stretching the same to suit the inequalities of the ground or other cause.

The principal novel features of my invention reside in the means for stretching all the fence-wires uniformly and simultaneously and for raising and lowering the point of draft on the adjacent portion of the fence during the operation of stretching.

Similar reference-numerals indicate like parts in the accompanying drawings, in which

Figure 1 is a side view of my invention in position for use with the adjacent end of the wires shown in dotted outline in the position to which they are adjusted when stretched and in position for stapling them to the post.

Fig. 2 is a plan view of the same, showing the construction by which the opposite co-operating claws of the operating-lever are adapted for an alternate actuating engagement with

the fence-connecting means. Fig. 3 is an enlarged perspective detail of the means for raising and lowering the point of draft on the adjacent end of the fence and its connection with the actuating means.

Referring now particularly to Figs. 1 and 2, my invention is adapted to be employed in connection with any suitable fence-clamp, the one shown being of common form and 65 consisting of a pair of vertical plates 1, rigidly held in a spaced parallel relation by means of the transverse bolts 2, and a pair of rods 3, pivotally connected at their bifurcated ends to the opposite ends of the plates 70 1 and loosely connected at their adjacent ends by means of the ring 4, to which is loosely secured one end of a chain 5, the other end of which is engaged by the stretching means. The fence on which the said clamp is mounted may consist of a series of longitudinal wires 6, as shown, or it may consist of a woven-wire fence of well-understood construction.

To that face of the fence-post 7 opposite to 80 the fence are pivotally mounted in any proper manner the outer ends of the oblique arms 8 and 9, identical in construction and provided upon their inner ends with the loosely-mounted stirrups 10, having their respective base- 85 plates 11 and 12, provided upon their inner ends with the respective apertured ears 13 and 14, which are pivotally connected with the bifurcated end of the clevis 15, which is arranged to project rearwardly between the 90 stirrups 10, as shown in Fig. 3. These parts are hinged or pivotally connected together by means of the bolts 16 and secured thereon by a nut 17.

The arms 8 and 9 are provided with a longitudinal slot 18, through which projects and in which is slidably arranged the respective studs or rigid bolts 19 and 20 of the stirrups 10. These arms are also provided with a metallic slotted plate 8'. On the outer end of these studs are arranged the washers 21 and 21', which have a bearing on the plate 8', and the respective tail-burs 22 and 23, by means of which the inner ends of these arms are afforded a limited longitudinal adjustment on the respective stirrups 10, for the purpose hereinafter described. The arm 8 is also preferably provided upon the outer face of its upper end with a hook 38, adapted to secure a rope 37, which is fastened to the top of the post 7, for the purpose of better securing the upper end of the arm 8. A lateral brace

or leg 24 has a suitable hinge 25 upon its upper end, which hinge is also mounted upon one end of the bolt 16 and is rigidly secured thereon by means of the nut 17. The lower 5 end of this leg is preferably pointed to be inserted in the ground, as shown at 26.

To the loop end of the clevis 15 is loosely connected the loop end of a second clevis 27, whose bifurcated end is pivotally connected 10 to the laterally-enlarged head 28 of the operating-lever 29 by means of the bolt 32 and has a proper handle 30, which is removably mounted in the socket 31, Fig. 2.

On the opposite ends of the lever-head 28 15 are pivotally mounted the inner ends of the clutch-arms 33 and 34 of identical construction, whose outer ends are provided with bifurcated claws adapted to alternately engage the outer end of the chain 5 during the 20 operation of tightening up the wire fence in the manner about to be described.

The operation and manner of employing my invention thus described are obvious, and, briefly stated, are as follows: The fence- 25 clamp is first adjusted upon the adjacent end of the fence with the wires secured between the plates 1 thereof. The outer ends of the arms 8 and 9 are provided with a claw-plate 35, whose pointed end is adapted to be temporarily inserted into the adjacent face of the post 7, as shown in Figs. 1 and 2. The operator then hooks the claw 34 into the free end of the chain 5, as shown in Fig. 2, and draws the chain and fence forward by means of the 30 hand-lever 29. This operation throws the handle of the lever forward and the other claw 33 rearwardly into a position in which it can readily be engaged with the chain 5 at a point nearer the fence-clamp, when by 35 moving the lever rearwardly into the position shown in Fig. 2 there will be another forward movement of the fence, after which the claw 33 will be disengaged and the claw 34 again engaged with the chain 5. By a suitable 40 repetition of these movements of the operating-lever the fence can be stretched past the post 7, or until all the slack is taken out of it, after which the lever is locked in any desired holding position by inserting a pin in 45 the one of the holes 36 in the head 28 of the operating-lever, Fig. 2. The operator can then conveniently staple the wires to the post 7. The lateral obliquely-arranged brace or leg 24 prevents any undue lateral 50 strain or displacement of the arms 8 and 9 in the direction toward the operator, and the chain 5 will obviously prevent any swing or displacement of these arms in the other direction in use. When it is desired to elevate 55 the point of draft on the fence, as in case of inequalities of the ground or other cause, it

can readily and conveniently be done by loosening the tail-bur 22, after which the strain of the draft upon the corresponding stirrup 10 will aid in sliding the same upward on the arm 8, thereby correspondingly elevating the draft-point and the adjacent 65 end of the fence. When it is desired to lower the point of the draft, it is done in a similar manner by loosening the tail-bur 23. 70

Having thus described my invention and the manner of employing the same, what I desire to secure by Letters Patent is—

1. In a wire-fence-stretching device the combination with an upright fence-clamp of 75 a pair of oblique arms adapted to be temporarily secured at their outer ends to a supporting-post, and having their inner ends pivotally connected; means for pivotally connecting the fence-clamp with the oblique 80 arms at or near their inner adjacent ends; and means for affording a longitudinal adjustment of the inner ends of said arms relative to their pivotal connection for the purpose of vertically adjusting the point of draft 85 as described.

2. A wire-fence-stretching device consisting of an upright fence-clamp; a pair of oblique arms adapted to be temporarily secured to a support and pivotally connected 90 at their inner ends to a draft device; means for pivotally connecting the draft device to the fence-clamp; means for imparting to the draft device a vertical adjustment; and means for resisting the lateral strain upon 95 the draft device to prevent derangement thereof.

3. The combination, in a wire-fence-stretching device of an upright fence-clamp; a pair of oblique arms adapted to be temporarily secured at their outer ends to the fence-post on which the adjacent end of the fence is to be secured, and having their inner adjacent ends pivotally connected and adapted for a limited longitudinal adjustment relative to their pivotal connection; a draft device pivotally connected to the connecting means of the two arms; means for connecting the draft device to the fence-clamp; means for actuating the said connecting means between the draft device and the fence-clamp; and means for imparting to the draft device a vertical adjustment for the purpose described. 105 110 115

Signed by me at Kendallville, Noble 115 county, State of Indiana, this 17th day of March, A. D. 1906.

ANDREW ADAM.
